UNITED STATES PATENT OFFICE.

SAMUEL KANNER AND SAMUEL JAFFE, OF NEW YORK, N. Y.

HAT PAD.

Application filed May 27, 1924. Serial No. 716,110.

To all whom it may concern:

Be it known that we, SAMUEL KANNER and SAMUEL JAFFE, both citizens of the United States, and residents of the city, county, and 5 State of New York, have invented certain new and useful Improvements in Hat Pads, of which the following is a specification.

This invention relates to hat pads and more particularly to a device of that character shown and described in Patent No. 10 1,482,685 issued to us on February 5th, 1924, which is specially designed and intended for use in connection with ladies' hats.

In the device shown in the above patent, 15 there is provided a stiffening member having padding on one side thereof held in position by a covering sheet enclosing the padding and the stiffening member. On the opposite side of the stiffening member a 20 metal attaching strip is secured, said strip having spaced prongs struck therefrom adapted to enter the hat brim. It has been found that owing to the fact that this metal attaching strip is of tempered steel, that 25 these prongs readily bend and break off.

It is the primary object and purpose of the present improvement to provide an attaching prong whereby the pad may be secured to the hat brim which consists of a 30 separate part fixed to the tempered metal strip, said prong preferably being constructed of cold rolled steel so that it is relatively hard and will not readily bend or break.

It is another object of our invention to 35 provide a single connecting means whereby the covering sheet for the padding, the resilient metal strip and the attaching prong, are rigidly secured to each other and connected to the stiffening member.

With the above and other objects in view, 40 the invention consists in the improved hat pad and in the form, construction and relative arrangement of the several parts as will be hereinafter more fully described, illustrated in the accompanying drawing and 45 subsequently incorporated in the subjoined claims.

In the drawing wherein we have illustrated one simple and satisfactory embodiment of the invention and in which similar 50 reference characters designate corresponding parts throughout the several views:

Figure 1 is an elevation of the hat pad provided with our present improvement; 55 Figure 2 is an enlarged sectional view taken on the line 2-2 of Figure 1; and,

Figure 3 is a detail perspective view of one of the prong members.

In the drawing, the hat pad, generally indicated by the numeral 5, is of substantially 60 the same construction as shown in our issued patent and for the purpose of this present explanation it will suffice to state that this pad includes a stiffening member 6 of cardboard or other suitable material having a 65 padding or cushioning material 7 on one side thereof, said material and the stiffening member being covered and enclosed within the fabric 8.

Upon the opposite or rear side of the 70 stiffening member and on the exterior of the fabric 8, the spring metal strip 9 is located contiguous to and in parallel relation with one longitudinal edge of the pad and extends for substantially the full length 75 thereof.

In conjunction with this spring metal strip, we employ the prong members 10, each of which is formed from hardened cold rolled steel and consists of a disc 11 having 80 a prong 12 formed on its edge and projecting at substantially right angles to the plane of said disc. This disc 11 is also provided with an eccentrically located opening 13.

The spring metal strip 9 has suitably 85 spaced openings formed therethrough corresponding in number to the number of the prong members to be used, and said members are arranged upon said strip with the openings 13 in registration with the openings of the strip. The spring metal strip and the prong members are then securely and permanently fixed to the stiffening member 6 by means of the metal grommets 14. In this manner it will be seen that the several parts 90 95 may be securely connected in fixed relation with each other in a single operation.

When the pad is arranged in the hat in the manner referred to in our issued patent, the projecting prongs 12 on the edges of the 100 discs 11 are forced through the hat brim, and owing to the fact that these prongs are of hardened steel, the necessary pressure may be applied without danger of bending or breaking the prongs from the edges of 105 the discs. Therefore, the pad will be at all times securely held and retained in its proper position within the hat.

From the foregoing description considered 110 in connection with the accompanying drawing, the construction and manner of use of our present improvements will be fully

understood. While we have herein specifically referred to the new attaching prongs for use in connection with the resilient metal strip as applied to a hat pad, it is to be understood that we do not desire to be limited to the exact form and construction of the parts as herein described, but reserve the privilege of resorting to all such legitimate changes in the form, construction and relative arrangement of the several parts as may be fairly embodied within the spirit and scope of the invention as claimed.

We claim:

- 15 1. In combination with a hat pad having a stiffening member, attaching means for said pad consisting of a resilient metal strip extending longitudinally of said stiffening member, spaced pointed spur members projecting outwardly each having a base portion provided with an opening, said strip having openings therein with which the openings in said base portions are adapted to register, and a common means extending through each of said openings of the spur members and the metal strips and through said stiffening member and rigidly connecting said stiffening member, the resilient metal strip and the spur members with each other.
- 20 2. In combination with a hat pad having a stiffening member, attaching means for said pad consisting of a resilient metal strip ex-

tending longitudinally of said stiffening member, spaced pointed spur members projecting outwardly each having a base portion provided with an opening, said strip having openings therein with which the openings in said base portions are adapted to register, and metal grommets extending through each of said openings of the spur members and the metal strips and through the stiffening member and rigidly connecting said stiffening member, the resilient metal strip and the spur members with each other.

3. In combination with a metal attaching strip having spaced openings therein, pointed spur members projecting outwardly each consisting of a hardened metal disc having a sharp spur projecting from the edge of the disc and at substantially right angles thereto so as to project into a member to which the attaching strip is to be secured, the disc having an opening therein to register with one of the openings in said metal strip, and means engaged through each of said openings of the spur members and the metal strips and rigidly connecting the spur members and the strip to each other.

In testimony that we claim the foregoing as our invention, we have signed our name hereto.

SAMUEL KANNER.
SAMUEL JAFFE.
